MIXED GETTER DEVICES, WITH EVAPORATED AND NOT EVAPORATED GETTERING MATERIAL, FOR MAINTAINING THE VACUUM IN ELECTRONIC TUBES

Paolo Della Porta, Via Gallarate 215, Milan, Italy
Filed Apr. 13, 1961, Ser. No. 102,754
6 Claims. (Cl. 265—4)

This invention relates to an improvement in getter devices for maintaining the vacuum in electronic tubes, and more particularly, in getter devices of the mixed type having a closed form, such as circular, ring or disc like, containing a portion of evaporable, and a portion of non-evaporable gettering material. Examples of this type of mixed getter device are described and illustrated in FIGURES 9 and 10 of Italian patent application No. 9,283 of December 29, 1960. One of the problems of the utilisation of non-evaporable gettering material is the necessity of activating it at high temperatures. The invention of the aforesaid application No. 9,283 relates to the problem of maintaining the non-evaporable getter at the necessary operating temperature after the activation. This invention relates, on the contrary, to the problem of activating the non-evaporable getter. While operating temperatures between room temperature and 800° C. are required for non-evaporable getters, the temperatures required for activating these non-evaporable getters range between 600° and 1500° C.

These last mentioned temperatures can be obtained by H.F. (high frequency) induced currents that travel on the closed loop provided by the external periphery of getter devices of closed form, such as ringlike or disclike. This invention, therefore, consists of an improvement to a mixed getter device of closed form with a portion of evaporable gettering material disposed within a peripheral groove of a getter device of the already known type, and with a portion of non-evaporable gettering material disposed within a second circular groove, disposed either interiorly or exteriorly concentric of the said first groove and in proximity of the same. In this way, the H.F. currents, used for the evaporation of the evaporable portion of the getter, are used in the same time for activating the non-evaporable portion of the getter. The positioning of the second groove, more or less near the peripheral groove containing the evaporable portion, provides the means to accordingly control the temperature of the non-evaporable gettering material contained within said second groove.

In the attached figures there are illustrated several embodiments of the invention. In said drawing:

FIGURE 1 shows a disc shaped getter device with an external peripheral upset portion defining an upwardly open groove containing an evaporable gettering material 1, and with a second upset portion defining a downwardly open groove, internally concentric with respect to the first one, and containing a non-evaporable gettering material 2;

FIGURE 2 also shows a disclike getter device similar to that of FIGURE 1, wherein instead of the second groove, a circular aperture is foreseen within which a body of non-evaporable gettering material 2, in the form of a flat ring, is pressed; in this manner both the upper and lower flat surfaces of the ring 2, as shown, of non-evaporable gettering material are exposed;

FIGURE 3 is an annular getter device with a peripheral

2

upwardly open groove containing an evaporable gettering material 1, and a second downwardly open groove, internally concentric with respect to the first one, containing a non-evaporable gettering material 2;

FIGURES 4, 5, 6 and 7 represent additional embodiments of annular getter devices with directing ribs for the vapors of the evaporable gettering material 1, directed inwardly of the ring, wherein the second groove containing the non-evaporable gettering material 2 is located internally concentric with respect to said ring, and is constituted by bending the internal directing rib so as to form said second groove;

FIGURES 8 and 9 represent further forms of annular getters with directing flanges for the vapors of the evaporable gettering material 1, directed inwardly of the ring, wherein the second groove containing the non-evaporable gettering material 2 is located externally of the ring, and is constituted by bending the external directing flange so as to form said second groove.

Of course, the position of the second groove containing the non-evaporable gettering material 2 will be provided in accordance with the requirements dictated by the geometry for positioning the device within the electronic tube, within the spirit and purpose of this invention, which lies in the utilisation of H.F. currents for both the evaporation of the evaporable gettering material, and simultaneously for activating the non-evaporable gettering material of a getter device of the mixed type. The spacing between the respective grooves containing the getter materials determines the relative heating of the two materials, since the high frequency induced currents tend to flow along the outermost peripheral portions of the getter containers.

What I claim is:

1. In a mixed getter device for maintaining a vacuum in electronic tubes including an evaporable gettering material and non-evaporable gettering material, a getter container means having a shape defining a closed peripheral path for the purpose of carrying induced high frequency heating currents, a first upset portion on said container coextensive with said peripheral path defining a first groove, said first groove containing an evaporable gettering material, and a second upset portion on said container coextensive with said first upset portion and selectively spaced therefrom defining a second groove, said second groove containing a non-evaporable gettering material, whereby said high frequency currents in said closed peripheral path simultaneously evaporate and activate, respectively, said evaporable and non-evaporable gettering materials.

2. The invention defined in claim 1, wherein the spacing between said first and second upset portions is selected dependent upon the vaporization and activating temperatures, respectively, of said evaporable and non-evaporable gettering materials.

3. The invention defined in claim 1, wherein said container comprises a circular disc.

4. The invention defined in claim 1, wherein said second upset portion is perforated to provide an aperture therein and wherein said non-evaporable gettering material is mounted in said aperture.

5. The invention defined in claim 1, wherein said second upset portion is formed by further upsetting a part of said first upset portion.

6. The invention defined in claim 1, wherein said first upset portion includes peripheral directing flanges for the vapors from said evaporable gettering material therein,

and further wherein said second upset portion is formed by upsetting one of said directing flanges.
